UNITED STATES PATENT OFFICE.

ANTON REZNICEK, OF JERSEY CITY, NEW JERSEY, ASSIGNOR TO HIMSELF, AND MAX MEYENBERG AND SOPHIE ERDMANN, OF HOBOKEN, NEW JERSEY.

POCKET-BOOK.

SPECIFICATION forming part of Letters Patent No. 616,492, dated December 27, 1898.

Application filed September 19, 1898. Serial No. 691,302. (No model.)

To all whom it may concern:

Be it known that I, ANTON REZNICEK, a citizen of the United States, and a resident of Jersey City, Hudson county, New Jersey, have 5 invented certain new and useful Improvements in Pocket-Books, of which the following is a specification.

This invention relates to a pocket-book, purse, chatelaine bag, or similar article of 10 novel construction, and more particularly to the means for connecting the lower edges of the covers or partitions with one another.

Briefly stated, my invention consists in providing the pocket-book with a slotted tubular 15 clamp-bar which embraces the lower edges of the partitions or covers to form a rigid bottom or hinge joint. Thus by my invention the manufacture of the pocket-book is simplified, while its strength is greatly increased.

20 In the accompanying drawings, Figure 1 is a transverse section of a pocket-book provided with my improvement on line 1 1, Fig. 4; Fig. 2, a perspective view of the clamp-bar *e*; Fig. 3, an end view of the pocket-book, showing it closed; Fig. 4, a section on line 4 4, Fig. 3; and Fig. 5, an end view of the pocket-book body without the frame and clamp-bar.

The body of the pocket-book is provided 25 with the usual partitions *a a' a² a³*, &c., to form the intervening compartments or pockets. In the "combination" pocket-book illustrated in the drawings an additional closing-flap *b* is attached to one of the outer partitions, while with the ordinary or plain pocket-book such flap is dispensed with, the two outermost partitions *a a³* themselves forming the covers.

30 *c c* are the jaws of the U-shaped frame, which engage the top and side edges of the covers *a a³*, such jaws being of a height equal to that of the book, so that they extend to the bottom of the same, Fig. 3.

The lower free edges of the partitions and covers *a a'*, &c., projecting below the gussets

d, Fig. 5, are engaged by a rigid tubular clamp-bar *e*, Fig. 2, preferably made of metal, which is provided with a longitudinal slot *e'*, through which all of such edges enter into the hollow of the bar.

After the tubular bar has been slid into place it is laterally compressed to decrease the size of its slot and to thus securely confine and connect the lower edges of the partitions. In this way a solid bottom for the pocket-book is formed, which not only increases its 55 strength but provides simple means for connecting its partitions into a common hinge-joint.

The tubular bar *e* should be so placed that it is centered substantially around the frame-pivots *c*, Fig. 4, so that its ends are inclosed and concealed by the shanks of the frame and that it does not bulge below the body of the pocket-book.

If desired, the outer covers *a a³* may be provided with bellows *f*, Fig. 5, to increase the capacity of the compartments, when manifestly the flanges *f'* of such bellows and not the covers themselves, will be engaged by the frame *c* and the clamp-bar *e*.

70 What I claim is—

1. A pocket-book or similar article having a frame, and a lower clamp-bar arranged between the shanks of the frame and embracing the lower edges of the pocket-book, substantially as specified.

2. A pocket-book or similar article having partitions with lower free edges, a tubular clamp-bar embracing and connecting such free edges, and a frame embracing the clamp-bar, substantially as specified.

Signed by me at New York, N. Y., this 15th day of September, 1898.

ANTON REZNICEK.
